COMBINED ALTAR AND PRAYER BENCH

Madeleine M. Shaw, 950 Yonge St., Toronto,
Ontario, Canada

Filed Dec. 11, 1959, Ser. No. 58,634

Term of patent 14 years

(Cl. D29—23)

FIG. 1

FIG. 2

Fig. 1 is a view in perspective of the combined altar and prayer bench showing the table-top leaves and the kneeling stools unfolded for use; and

Fig. 2 is a similar perspective view but showing the table-top leaves and the kneeling stools folded.

The dominant features of my design are shown in full lines.

I claim:

The ornamental design of a combined altar and prayer bench, substantially as shown and described.
